[57] CLAIM

The ornamental design for a combined clothes washer and drier, as shown and described.

DESCRIPTION

FIG. 1 is a top plan view of the combined clothes washer and drier showing our new design;

FIG. 2 is a top plan view thereof with covers open;

FIG. 3 is a bottom plan view thereof;

FIG. 4 is a front elevational view thereof;

FIG. 5 is a rear elevational view thereof;

FIG. 6 is a right side elevational view, the left side elevational view being a mirror image thereof; and

FIG. 7 is a perspective view thereof.
